UNITED STATES PATENT OFFICE.

EGBERT N. CLARK, OF ROCHESTER, NEW YORK.

PROFILE-DEFINING APPARATUS.

Application filed February 28, 1922. Serial No. 539,894.

To all whom it may concern:

Be it known that I, EGBERT N. CLARK, a citizen of the United States, and resident of Rochester, in the county of Monroe and 5 State of New York, have invented certain new and useful Improvements in Profile-Defining Apparatus, of which the following is a specification.

The present invention relates to a profile defining apparatus and while more particularly designed for teaching characterology, it is also capable of use for amusement purposes or for the teaching of drawing. An 10 object of this invention is to provide a profile defining apparatus capable of adjustment to produce, from a number of relatively adjustable profile segments, a large variety of complete outlines or profiles. Another object of the invention is to make the 15 profile segments interchangeable with other segments whereby may be obtained a substantially unlimited number of different complete outlines or profiles. Still another object is to provide in connection with each 20 of the profile segments, an indicating means which may be used in connection with a chart to point out the general character of a person having a profile corresponding to the one delineated by the adjustment. 25 To these and other ends, the invention consists of certain parts and combinations of parts, all of which will be hereinafter described: the novel features being pointed out in the appended claims.

30 In the drawings:

Fig. 1 is a face view of an apparatus constructed in accordance with this invention;

Fig. 2 is an edge view of the apparatus;

Fig. 3 is a section on the line 3—3, Fig. 1;

40 Fig. 4 is a section on the line 4—4, Fig. 1;

Fig. 5 is a detail view of the tool through which adjustments may be made;

Fig. 6 is a detail view of the slide on which the chin and mouth defining member 45 is mounted to turn;

Fig. 7 is a detail view of one of the crown defining members;

Fig. 8 is a detail view of one of the forehead defining members;

50 Fig. 9 is a detail view of one of the nose defining members;

Fig. 10 is a detail view of one of the mouth and chin defining members;

55 Fig. 11 is a detail view of one of the ear defining members;

Fig. 12 is a detail view of the base showing the profiling members removed;

Fig. 13 is a section on the line 13—13, Fig. 12;

Fig. 14 is a fragmentary view showing 60 some of the profile defining members in position on the base;

Fig. 15 is a detail view of one of the rear head and neck defining members; and

Fig. 16 is a fragmentary view showing the 65 manner in which the forward crown piece is connected with the rear head and neck defining member, when the profiles on these two members do not coincide.

In the illustrated embodiment of the invention there is employed a base member 1 and a frame 2 with an opening through which the profile is viewed. Arranged on the base member 1 under the frame 2 is a sheet 3 formed with a circular opening 4, 70 part of which extends under the frame while the major portion of it lies within the opening of the frame 2. In this circular opening 4 is adapted to be received, a circular disk 5 formed on one or both sides with a line or other mark 6 which will form on each side of the center of said disk a forehead defining line. This disk with the line 6 thereon will be termed a "forehead defining member." It is obvious that the portions of the line on 75 each side the center of the disk may be employed for forming or defining the forehead of two profiles, and, by inverting the disk a similar line on the opposite side may be employed for giving two other profiles of the forehead. Other disks may be employed 80 having still other profiles for the forehead. Each profile defining portion with the line 6 is given a number indicated at 7 and on the sheet 3 at the perimeter of the disk, 85 graduations 8 are provided with which the end of the profile being delineated may cooperate. The number of the profile with the position of the profile with reference to said 90 graduations can, by reference to a chart 95 which may be used in connection with an apparatus, give in a general way the character of a person provided with such profile at the forehead.

The sheet 3 may also be provided with an 100 arcuate recess 9 of less depth than the opening 4 and of greater diameter than the said opening, the center of said arcuate recess being coincident with the center of turning 105 of the disk 5. A nose defining member 10 110

is adapted to be received in the opening 4 to extend into arcuate recess 9 over the forehead defining member 5, so that a nose profile 11 on said member 10 may have the upper portion thereof, coincident with the lower portion of the profile 6 on the forehead defining member while covering that portion of the disk 5 not being used at this time. It will thus be seen that the forehead defining member and the nose defining member turn about a common axis which is coincident with the point or junction between the two profiles on the two members. It is apparent that the nose defining member may have a profile on each side thereof, and that other members with other profiles may be substituted. Each nose defining member 10 may be provided with a character 12 and an index or pointer 13, the latter cooperating with graduations 14 formed on the sheet 3 adjacent the perimeter of said nose defining member 10. The character 12 together with the graduations 14 are employed in connection with the chart hereinbefore mentioned for determining the character of a person having a profile corresponding to the profile delineated by the nose forming member.

Arranged to cooperate with the nose defining member is a chin and mouth defining member 15, which has a chin and mouth profile 16 thereon. This member is, in this instance, in the form of a segment of a disk and may have on either or both sides thereof of a profile. Other members with different shapes of profiles may be substituted for the illustrated member 16. In order that this member may move about an axis and also shift bodily, so that the position of this axis may be changed to correspond to the position of the lower portion of the profile on the nose defining member 10, a slide 17 may be provided. This slide, in this instance is mounted to operate in a guideway formed between the frame 2 and the base 1. Two curved recesses 18 and 19 are provided in the slide, these recesses having the same radius but having their centers so arranged that the center of rotation may be shifted with reference to the nose defining member thus still further increasing the range or scope of the apparatus.

A chin or mouth defining member 15 is received within either of said recesses and is mounted to turn in engagement with the curved walls of the recess so that the desired angle for the chin may be obtained. The slide is moved so that the lip portion of the member 15 may coincide with the lip portion on the nose defining member 10. Each chin and mouth defining member 15 has a character 20 thereon and a pointer or index 21 which is adapted to cooperate with graduations 22 formed on the slide 17 adjacent the recess 18. Graduations for the

recess 19 are provided on the opposite side of said slide, which is removable from the guideway and invertible so that the recess 19 may be employed when desired.

The forward crown, in this instance, is defined by a member 23 which has a crown profile 24 on either or both sides thereof. Other forward crown defining members may, of course, be provided to give other forward crown profiles. This forward crown defining member 23 rests upon the sheet 3 and is preferably held thereon by a spring finger 25. The forward crown profile 24 extends to opposite ends of the member, one end being adapted to be positioned to coincide with the upper end of the profile 6 of the forehead defining member 5. The opposite end of the profile 24 on the profile defining member 23 is adapted to form an index to cooperate with graduations 26 on the sheet 3. Each forward crown defining member 23 has a mark or character 27 thereon, and this character with the graduations 8 and 26 may be used in connection with the chart heretofore mentioned for the purpose of ascertaining the character of a person having such a forward crown profile.

For defining the rear head and neck, any number of members 27 may be employed having a rear crown and neck profile 28 thereon. This member 27 is movable bodily so that one end of the profile 28 may coincide with a portion of the profile 24 on the forward crown defining member 23. In this instance, the guideway 29 is provided beneath the frame 2 so that the member 27 may be moved toward and from the face portion of the profile. Graduations 30 may be provided on the sheet 3 for cooperation with each of the members 27, and these graduations together with the character 31 on the member 27 may be employed in connection with the chart heretofore mentioned for the purpose of determining the probable character of a person having a profile defined by the adjusted position of the member 27. The member 27 is flexible laterally so as to be withdrawn from its position over the sheet 3. A spring clip 32 carried by the frame 2 may cooperate with the member 27 to hold the latter in its adjusted position.

In some instances the profile on the forward crown defining member will not coincide with the profile on the rear head and neck defining member, and in order to provide the connection between these parts, there may be employed a rear crown defining member 45 which may also be held in position by the clip 32.

For defining the ear any number of members 33 may be provided having an ear profile 34 thereon. This member 33 is mounted to move with the member 27 and is preferably removable from said member and also adjustable thereon. This result is secured

by providing the member 27 with a curved notch 35, the walls of which form the segment of a circle. The member 33 has its edge curved to conform to said wall so that 5 the member 33 may be turned to secure the proper angle for the ear. Graduations 36 are provided on the member 27 for cooperation with a pointer 37 on the member 33. These graduations together with the character 10 38 on the member 33 determine approximately the character of a person whose profile is defined by the member 33 and the adjustment thereof. A spring clip 39 on the frame 2 cooperates with the ear defining member 33 to hold the latter in its adjusted 15 position.

If desired some or all of the profile defining members may be provided with openings 40 and, into these openings the pointed 20 end 41 of an instrument 42 may be introduced to effect the adjustment of the members, the instrument also having a pointed end 43 which may also be used for adjusting the apparatus. The instrument, in order 25 to prevent the loss thereof may be connected by the chain 44 with the apparatus.

From the foregoing it will be seen that it is possible with this construction to substantially delineate the profile of any human 30 head. The profile of the head is divided up into a number of sections, each section being arranged upon a movable member. These members are so mounted that the angle of the profile section on the members 35 may also be obtained. The face portion of the profile is formed by sections of three different members, two of which are mounted to turn about a coincident axis at the junction between said sections, while the 40 other is movable bodily so as to be made to coincide with the profile section of one of said pivoted members while at the same time also pivotally mounted to obtain the angle of the profile section.

45 The members containing the facial sections of the profile, and a member containing the rear crown and neck sections of the profile are relatively adjustable so as to vary the distance between these parts. An intermediate front crown defining member connects the rear crown defining member and the members forming the facial sections of the profile.

50 While the invention has been described for delineating the profile to determine the character of a person, it is apparent that it is not limited to this use as it may be employed for amusement purposes, for the teaching of drawing, or for the delineating 55 or defining of profiles other than that of the human head.

What I claim as my invention and desire to secure by Letters Patent is:—

60 1. A profile defining apparatus comprising a plurality of relatively adjustable mem-

bers, each having a section of a profile thereon, two proximate members being mounted to turn about a common axis at the junction of the profile sections thereon, and the other members being shiftable bodily with reference to said two members. 70

2. A profile defining apparatus comprising a plurality of relatively adjustable members, each having a section of a profile thereon, two proximate members being mounted to turn about a common axis at the junction of the profile sections thereon, and the other members being shiftable bodily with reference to said two members, one of the bodily movable members being also mounted to turn about an axis coincident with that portion of its profile section which meets the profile section on said pivoted member. 75

3. A profile defining apparatus comprising a plurality of relatively adjustable members, each having a section of a profile thereon, two proximate members being mounted to turn about a common axis at the junction of the profile sections thereon, and the other members being shiftable bodily with reference to said two members, and a slide on which one of said bodily movable members is mounted to turn about an axis which is adapted to be positioned in coincidence with the profile section on one of said pivotally mounted members. 80

4. A profile defining apparatus comprising a plurality of relatively adjustable members, each provided with a profile section, one of said adjustable members having another of said adjustable members adjustable thereon. 100

5. A profile defining apparatus comprising a plurality of relatively adjustable members, two of said members being adjustable about a common axis coincident with the junction of the profile sections on the two members and another of said adjustable members being mounted to move toward and from said axis. 105

6. A profile defining apparatus comprising a plurality of relatively adjustable members, two of said members being adjustable about a common axis coincident with the junction of the profile sections on the two members and another of said adjustable members being mounted to move toward and from said axis and having still another of said members adjustable thereon about a suitable axis. 115

7. A profile defining apparatus comprising a plurality of members each having a profile section of a human head, means for supporting said members so that each member may assume a plurality of different positions with reference to an adjacent member to form different profiles, and means for indicating the adjustment of each member with reference to its adjacent member to permit the determining of the character of 125 130

the head defined by the different adjustments.

8. A profile defining apparatus comprising a plurality of adjustable members, each having a profile section of a human head, one of said members, on which is provided the rear head section and neck of the profile, being adjustable toward and from the members on which the facial sections of the profiles are delineated.

9. A profile defining apparatus comprising a plurality of adjustable members, each having a profile section of a human head, one of said members, on which is provided the rear head section and neck of the profile, being adjustable toward and from the members on which the facial sections of the profile are delineated and another of said members on which the ear is delineated being adjustable on the last mentioned member about a suitable axis to define the angle of the ear.

10. A profile defining apparatus comprising a plurality of adjustable members, each having a profile section of a human head, two of the members forming sections of the

facial part of the profile sections on said members and another of the members forming part of the facial portion of the profile being shiftable bodily so that its profile section may be made to align with the profile section of one of said pivotally mounted members, said last mentioned member being adjustable about an axis coincident with the portion of the profile section which coincides with the portion on the said one of the first two named pivotally mounted members.

11. A profile defining apparatus comprising a plurality of relatively adjustable profile defining members for delineating a human head, each provided with a profile section, two of said members forming sections of the facial portion of the profile being mounted to turn about a common axis at the junction of the two sections on the profile of the two members, and the two members on opposite sides of the said pivoted members being bodily adjustable in order that the profile sections thereon may be made to coincide with the profile sections on the pivotally mounted members.

EGBERT N. CLARK.
